UNITED STATES PATENT OFFICE.

JOSEPH LYNCH, OF PARSONS, KANSAS.

RAIL-BREAKING DEVICE.

1,057,862.

Specification of Letters Patent.

Patented Apr. 1, 1913.

Application filed August 16, 1911. Serial No. 644,290.

To all whom it may concern:

Be it known that I, JOSEPH LYNCH, a citizen of the United States, residing at Parsons, in the county of Labette and State 5 of Kansas, have invented new and useful Improvements in Rail-Breaking Devices, of which the following is a specification.

The present invention provides an appliance by the use of which railway rails, 10 angle beams and kindred metal bars may be quickly broken into short lengths at a saving of labor and time.

The invention consists of the novel features, details of construction and combination of parts, which hereinafter will be more particularly set forth, illustrated in the accompanying drawing, and pointed out in the appended claims.

Referring to the drawing, forming a part 20 of the specification, Figure 1 is a side view of an implement embodying the invention. Fig. 2 is a top plan view of the implement, a portion of the handle being broken away. Fig. 3 is a section on the line $x-x$ of Fig. 25 1, looking to the left. Fig. 4 is a section on the line $x-x$ of Fig. 1, looking to the right. Fig. 5 is a detail view, showing the manner of using the device.

Corresponding and like parts are referred 30 to in the following description, and indicated in all the views of the drawings, by the same reference characters.

The implement consists of a bar 1 which constitutes a lever, the same having an integral projection 2 near one end, said projection having a foot piece 3 to support the lever when in operation. One end of the lever is widened vertically, as indicated at 35 4, and has a slot 5 extending lengthwise thereof. A grapple 6 has its members connected by means of links 7 with the slotted end of the lever 1. The grapple 6 comprises two members which cross each other and are pivotally connected at the point of cross- 40 ing. When the ends of the members of the grapple are brought together the rail, beam, or other article to be separated is gripped between the jaws of the grapple and by reason of the great length of the long arm of 45 the lever from the projection 2 an extraordinary force is developed which causes separation of the rail at the required point.

In Fig. 5, which shows a practical application of the invention, two rails C are placed upon two rails A A' and the rail B 55 to be broken is placed upon the rails C. The implement is adjusted with the grapples engaging the head of the rail A and with the offstanding projection 2 engaging the web of the rail B. The base and the head of the rail B are nicked by means of a chisel and sledge and upon applying power to the outer end of the lever 1 the rail B is snapped in line with the nicks.

From the foregoing description, taken in 65 connection with the accompanying drawing, the advantages of the construction and of the method of operation will be readily apparent to those skilled in the art to which the invention appertains, and while I have 70 described the principle of operation of the invention, together with the device which I now consider to be the best embodiment thereof, I desire to have it understood that the device shown is merely illustrative, and 75 that such changes may be made when desired as are within the scope of the claims appended hereto.

Having thus described the invention what is claimed as new, is:—

1. A device of the character set forth comprising a lever having an offstanding part near one end, and having a longitudinally extending slot in its short arm, and a grapple arranged in the plane of the lever and having its members connected with the slotted end of the lever.

2. A device of the character set forth comprising a lever having an offstanding part near one end forming a long arm and a 90 short arm, and having the short arm formed with a longitudinally extending slot, a grapple arranged in the plane of the lever, and links connecting the members of the grapple with the slotted end of the lever.

In testimony whereof I affix my signature in presence of two witnesses.

JOSEPH LYNCH.
